(57) **CLAIM**

The ornamental design for a shower valve, as shown and described.

DESCRIPTION

FIG.1 is a front perspective view of a shower valve showing my new design;

FIG.2 is a rear perspective view thereof;

FIG.3 is a front view thereof;

FIG.4 is a rear view thereof;

FIG.5 is a left view thereof;

FIG.6 is a right view thereof;

FIG.7 is a top view thereof; and,

FIG.8 is a bottom view thereof.

The broken lines depict portions of the shower valve and form no part of the claimed design.
